GAME BOARD

Roland R. Remmel, Little Rock, Ark., assignor to Boise Cascade Corporation, Boise, Idaho, a corporation of Delaware

Filed Jan. 22, 1965, Ser. No. 83,527

Term of patent 14 years

(Cl. D34—5)

Fig. 1

The essential features of my design reside in the portions shown in solid lines on the drawing.

I claim:

The ornamental design for a game board, as shown and described.
